US00D926705S

(12) **United States Design Patent** (10) **Patent No.:** **US D926,705 S**
Musser et al. (45) **Date of Patent:** **** Aug. 3, 2021**

(54) **CONTACT**

- (71) Applicant: **Samtec, Inc.**, New Albany, IN (US)
(72) Inventors: **Randall E. Musser**, New Albany, IN (US); **Jonathan E. Buck**, New Albany, IN (US)
(73) Assignee: **SAMTEC, INC.**, New Albany, IN (US)
(***) Term: **15 Years**
(21) Appl. No.: **29/773,721**
(22) Filed: **Mar. 11, 2021**

Related U.S. Application Data

- (63) Continuation of application No. 29/652,012, filed on Nov. 5, 2018.
